CLAIM

The ornamental design for a bucket and stand set, as shown and described.

DESCRIPTION

FIG. 1. illustrates a top, front, left perspective view of a bucket and stand set showing the new design;

FIG. 2 illustrates a bottom, front, left perspective view thereof;

FIG. 3 illustrates a top, front, left perspective view with environment thereof;

FIG. 4 illustrates a front elevation view thereof, rear elevation view is a mirror image thereof;

FIG. 5 illustrates a left elevation view thereof, right elevation view is a mirror image thereof;

FIG. 6 illustrates a top plan view thereof;

FIG. 7 illustrates a bottom plan view thereof;

FIG. 8 illustrates a top, front, left exploded perspective view thereof;

FIG. 9 illustrates a bottom, front, left exploded perspective view thereof;

FIG. 10 illustrates an exploded front elevation view thereof, the rear elevation view is a mirror image thereof;

FIG. 11 illustrates an exploded left elevation view thereof, the right elevation view is a mirror image thereof;

FIG. 12 illustrates an exploded top plan view thereof; and,

FIG. 13 illustrates an exploded bottom plan view thereof. The broken lines illustrate the nesting edges, handles, and structural components of the bucket and form no part of the claimed design. The broken lines in FIG. 3 illustrate the surrounding environment, nesting edges, handles, and structural components of the bucket and form no part of the claimed design.

1 Claim, 12 Drawing Sheets
